UNITED STATES PATENT OFFICE.

WILLIAM C. WILLER, OF SWIFT CURRENT, SASKATCHEWAN, CANADA.

WRENCH.

1,236,802.

Specification of Letters Patent. Patented Aug. 14, 1917.

Application filed July 20, 1916. Serial No. 110,418.

To all whom it may concern:

Be it known that I, WILLIAM C. WILLER, citizen of the United States, residing at Swift Current, in the Province of Saskatchewan and Dominion of Canada, have invented certain new and useful Improvements in Wrenches, of which the following is a specification.

This invention has relation to ratchet wrenches, and the nature and objects thereof will be readily apparent to those skilled in the art to which it appertains, in the light of the following explanation of the accompanying drawings, illustrating what I now believe to be the preferred embodiment, or mechanical expression of my invention, from among other forms and arrangements within the spirit thereof and the scope of the appended claims.

20 However, an object of the invention is to provide a ratchet wrench embodying a wrench head for engaging a nut and a handle movable relatively to the head and having means whereby the handle may be oscillated to rotate the head in either direction.

Another object of the invention is to provide a wrench having the above named characteristics and in addition thereto relatively 30 movable jaws adapted to engage nuts and bolts of various sizes and shapes.

In addition to the foregoing, my invention comprehends improvements in the details of construction and arrangement of 35 parts to be hereinafter described and particularly pointed out in the appended claims.

In the accompanying drawings, in which similar and corresponding parts are designated by the same characters of references 40 throughout the several views in which they appear:

Figure 1, is a view in side elevation of a wrench constructed after the manner of my invention.

45 Fig. 2, is an end view.

Fig. 3, is a vertical section taken on the line 3—3 of Fig. 2.

Fig. 4, is a face view of the wrench head illustrating the relatively movable jaws, and

50 Fig. 5, is a horizontal section on the line 5—5 of Fig. 1.

With reference to the drawings, 1 indicates generally the head of my improved wrench, which comprises a tubular body portion 2 having its intermediate exterior

threaded as at 3, and oppositely disposed slots extending from the lower portion thereof to a point intermediate the length of the body portion as indicated at 4. The body portion is formed at its lower end with oppositely extending lugs 5 which are also slotted, said slots being the continuation of the slots 4.

The upper portion of the body portion is reduced as at 6, and threaded as at 7 to receive a knurled cap 8, interiorly threaded to engage the threads 7. The reduced portion is provided on its exterior with oppositely disposed longitudinal grooves 9, for the reception of lugs 10 formed radially and interiorly of an annular ratchet member 11 which encompasses the reduced portion. The annular member is obviously capable of longitudinal movement relative to the body portion while locked thereto against relative rotary motion.

The handle of my wrench indicated at 12 is provided at one end with spaced annular members 13 which encircle the body portion and receive therebetween the annular member 11. A stud or the like, 14 is provided between the annular members at a point diametrically opposite the point of connection of the handle to assist in retaining the annular members in proper spaced relation. The handle at the point of connection with the annular members 13 is formed with adjacent longitudinal openings 15 for the reception of sliding pawls 16 having their outer terminals adapted for engagement with the teeth of the annular member 11 and formed with beveled faces 17. The beveled faces of each pawl are inclined in opposite directions relative to each other for a purpose which will presently appear. The lateral faces of the handle 12 are formed with longitudinal openings 18 which intersect the openings 15, and pins 19 are passed through said openings and engage in the sliding pawls 16. Coil springs 20 are interposed between the inner ends of the pawls and the ends of their recesses. It will be obvious that either pawl may be retracted from engagement with the annular member 11 by moving its corresponding pin 19 against the tension of the spring, the pawl may then be retained in said position by engaging a pivoted hook member 21 secured to the lateral faces of the handle over the pin 19. The opening 18 may be de-

100
105
110

pressed as at 22 to receive the pin whereby the hook member 21 is assisted in retaining the pawl in retracted position.

Relatively movable coacting jaws 23 are provided at the lower portion of the head and are formed with shanks 24 which extend through the openings in the lugs 5 and are formed with upwardly converging portions 25, terminating in parallel upper terminals 26, disposed centrally within the tubular member 2 and pivoted at said terminals upon a transverse pin 27 supported at its ends in the upper portion of the member 2. It will be noted that the inclined or diverging portions 25 are disposed within the slotted portions 4 and extend beyond the circumference of the tubular member. For providing relative movement of the jaws, an annular internally threaded band 28 is adapted to engage the threaded portion 3 of the tubular member and is further provided with a lower outwardly flaring or conical flange 29. The said flange is adapted to engage the inclined portions 25 of the jaw shanks, and it will be obvious that owing to the longitudinal movement of the band 28 relative to the tubular member produced by rotating said band, the jaws may be moved toward each other when the band is moved downward, a spring 30 interposed between the shanks of the jaws acting to separate them when permitted by a reverse rotation of said band 28. The jaws 23 may be formed as in the present instance with semicircular serrated faces 31 whereby nuts and burs of various forms may be engaged therebetween and securely held during rotation of the wrench head. The lower portion of the head may be formed with lugs 32 extended in opposition and between the lugs 5. When the jaws are applied to a nut, the lugs 32 may act as a stop to limit further movement of the head.

To rotate the wrench head by means of the handle, one of the pawls 16 is permitted to engage the toothed periphery of the annular member 11 while the other pawl is disengaged therefrom and held in such disengaged position by its correlated mechanism described above. By oscillating the handle, it will be apparent that during its movement in one direction the extended pawl will engage the aforesaid teeth and upon a reverse movement the pawl will be automatically disengaged owing to the provision of the beveled end 17 whereby the pawl is moved into its recess against the tension of the spring. Obviously, if the

pawl in question is retracted and the other pawl disengaged from its retaining means and permitted to engage the teeth of the annular member, an oscillation of the handle will rotate the head in a counter-direction.

While I have illustrated and described my invention with some degree of particularity, I realize that in practice various alterations thereover may be made, and I therefore reserve the right and privilege of changing the form of the details of construction or otherwise altering the arrangement of the correlated parts, without departing from the spirit of the invention or the scope of the appended claims.

Having thus described my invention what I claim as new and desire to secure by Letters Patent is:

1. A ratchet wrench including a tubular exteriorly threaded head, longitudinal oppositely located grooves formed upon the exterior of the head adjacent one end thereof, a toothed annular member engaging said end and having radial lugs seated in the grooves, a cap engaged upon said end to prevent displacement of the annular member, a handle having annular members encircling the head and adapted to receive the annular member therebetween, pawls in the handle adapted for alternate engagement with the annular toothed member whereby the head may be rotated upon oscillating the handle, means for retaining the pawls out of engagement with the toothed member, and relatively movable jaws for the head.

2. A ratchet wrench including a tubular member slotted at diametrically opposite points longitudinally, slotted lugs formed integrally with the slotted end of the member, relatively movable jaws having shanks which pass through the slotted lugs, and through the slots of the tubular member in a direction at an angle to the longitudinal axis of the member, means for pivotally mounting the inner ends of the shank within the tubular member, a ring movable longitudinally upon the tubular member and engaging the angularly directed portions of the shank to move the jaws relatively, and a coil spring engaging the shanks to urge them apart.

In testimony whereof I affix my signature in presence of two witnesses.

WILLIAM C. WILLER.
